UNITED STATES PATENT OFFICE.

JAMES FARASEY, OF CLEVELAND HEIGHTS, OHIO.

APPARATUS FOR SCREENING AND GRADING MATERIALS.

Application filed March 26, 1923. Serial No. 627,578.

This invention is concerned with concrete mixing and screening devices and has for its object the provision of a novel sectional hopper or bin construction adaptable for the reception of screened concrete ingredients, each bin being arranged to receive material of a common screen size.

More specifically, my invention contemplates the provision of a sectional hopper construction adaptable for the reception of various sizes of concrete forming material, and screened sand, the arrangement of the partitions being such that when sand is being screened by the usual three or four grade rotary screening device, a plurality of the crushed stone receiving bins may be utilized for the storing of the sand after passing through the screens.

A further object of my invention is the provision of a hopper construction having the partition or partitions thereof, defining the bins as a hopper arranged to be adjustable, and having chutes or passages controlled by valves extending from one bin to another through the partitions whereby the bins may be used for the receiving and storing of several grades of crushed stone falling from a rotary screen or a number of the bins may be used for receiving and storing screened sand while other bins of the hopper receive the rejected or unscreened material.

Other objects will be hereinafter set forth in the following description referring to the accompanying drawings which illustrate a preferred embodiment of my invention. The essential characteristics are summarized in the claims.

In the drawings Fig. 1 is a cross sectional elevation illustrating the relation of a screening device and my hopper construction; Fig. 2 is a cross sectional plan view taken substantially along the line 2—2 of Fig. 1; Fig. 3 is an enlarged cross sectional elevation taken substantially along the line 3—3 of Fig. 2 and Fig. 4 is an enlarged perspective view of a valve construction establishing communication between the various bins comprising my hopper construction.

In the preparing and selection of ingredients for concrete which is used in road building and other construction work, it is frequently desirable to obtain ingredients

for a coarse aggregate, a fine aggregate, or a special aggregate concrete. The grading of the aggregate depends primarily upon the coarseness or fineness of the crushed stone elements in the aggregate and this grading is usually effected by passing the material through rotary screening cylinders. Likewise, it is frequently desirable to screen sand with the same apparatus and store the sand in hoppers as well as the refuse from the screening device, there usually being a number of bins in the hopper for storing the sand after having been screened as well as storing the refuse. In conditioning the apparatus for screening sand, however, it is necessary to remove the coarser screening cylinders and replace them with cylinders having smaller apertures for screening the sand. These cylinders are necessarily heavy and bulky and considerable time and labor are expended in making these changes.

I accordingly arrange a hopper beneath the usual rotary screen mechanism whereby the various sizes of crushed stone or gravel may be collected in bins or compartments formed in a hopper disposed therebeneath and I combine in the hopper construction a valve arrangement and chutes whereby communication may be established between two or more of the hopper bins. I also provide removable bin partitions so that when it is desired to screen sand, the partitions may be removed and the sand storing capacity of the hopper greatly increased. On the other hand, when several sizes of screened material are being received from the screening cylinders, this material may be kept separated and be directed to the respective storage bins of the hopper through chutes.

Referring to the drawing, in Fig. 2, I show an elevator E, the buckets 10 of which may discharge their contents of crushed stone or gravel into an elevated chute 11, which guides the unscreened material to the interior of a screening cylinder 12. The screening cylinder is rotatably mounted upon rollers 13 and may be rotated by any suitable power means. The receiving end of the screen is elevated whereby the material may progress through the interior thereof and pass through the various sized openings formed in the cylinder walls. The

screening device illustrated, is adaptable for the selecting of or screening of four sizes of crushed stone, which for convenience of illustration may be $\frac{1}{8}$ inch; $\frac{3}{8}$ inch, 1 inch and 2 inch and over sizes.

The end of the cylinder, adjacent the elevator, may have perforations formed therein to permit the passing of the $\frac{3}{8}$ inch size. Surrounding this portion of the cylinder may be a second cylinder in the form of a jacket 14 which has perforations therein corresponding to a $\frac{1}{8}$ inch size. A second jacket 15, surrounding the lower end of the screening cylinder 12, may have openings formed therein corresponding to a 1 inch size.

The hopper construction and chutes for receiving the various sizes of crushed stone may be such that the hopper may be disposed directly beneath the cylinder whereby some of the screenings may fall directly into the storage bins of the hopper while other sizes may flow through chutes into other bins. The screening cylinder 12, therefore, may be mounted at a sufficient height upon pedestal members 16 and 17 whereby a substantial storage space may be provided in the hopper bins, and to permit positioning of a vehicle beneath the hopper.

To facilitate the receiving and storing of the screened material as it flows downwardly into the hopper from the screening cylinders, I arrange the hopper with the bins thereof in an offset relation relative to the cylinders. As shown in Fig. 3, the hopper 20 may be divided into four compartments or bins by interior walls 21 and 22 extending substantially the height of the hopper and terminating at the bottom thereof in valves as will be described.

Extending from adjacent the ends of the outer screening cylinders 14 and 15 are chutes formed by members 23 and 26, respectively, which slope toward the partition wall 22, and terminate in wall openings 27 and 28 respectively. The chute 23 guides the material from the $\frac{3}{8}$ inch screening cylinder to the bin 30, while the relative position of the screening cylinders to the hopper are such that the $\frac{1}{8}$ inch screenings drop directly into the bin 31 and the 1 inch screenings, from the cylinder 15, drop directly into the bin 32. The 2 inch and larger screenings are guided by the chute 26 to the refuse bin 33.

The lower portion of the hopper 20 has the walls thereof sloping inwardly and terminating at valves as shown at 35 in Fig. 3. These valves may comprise closure members 36 mounted upon pin members 37 secured to a frame member 38 attached to the lower end of the hopper. The members 36 extend across and close openings of nozzle members 40 which are carried by the frame 38. If it is desired, a vehicle may be positioned beneath the nozzle openings and material

stored in any one of the bins may be discharged directly into the vehicle by opening the nozzles.

It is frequently desirable however, to use the device for screening sand and in the particular arrangement illustrated in the drawing, it will be noted that the sand when screened will pass through the cylinder 14 and fall directly into the bin 31. The refuse material would pass into the bins 30, 32 and 33, and since the volume of rejected material is greatly less than the amount of sand passing through the screen 14, the bin 31 would be filled while the remaining bins would be comparatively empty. To utilize a greater portion of the hopper for storing the screened sand, I arrange the partition wall 22 between the bins 30 and 31 whereby a section 22^a of the wall may be swung to the dot and dash position as indicated in Fig. 2 in juxtaposition to the partition wall 21, thus obtaining a large bin for the storage of the screened sand which is substantially equal to half the storage capacity of the hopper. The partition wall section (22^a) may be hingedly connected to the partition wall 21 at substantially the vertical center line of the hopper. Any suitable means such as a latch 62, may serve to retain the partition section (22^a) in the position illustrated in Fig. 2 when it is desired to use the screening device for other purposes than for screening sand.

When the device is used for screening sand, it is important that the refuse material falling into the chute 23 from the screen cylinder 14 be directed into either the bin 32 or 33.

I therefore incorporate a valve mechanism in the hopper construction which may be associated with the lower portion of the chute 23 whereby the $\frac{3}{8}$ inch screenings (refuse when screening sand) may be discharged directly into the 1 inch storage bin which receives refuse from the cylinder 15.

The valve mechanism may comprise a closure member 45 slightly larger in dimensions than the opening 27 formed in the chute wall 25^a and a second closure member 46 extending normal to the member 45 and comprising a sector adapted to close an opening 47 formed in the partition wall 21 and which establishes communication between the chute 23 and the 1 inch storage bin 32. The closure members 45 and 46 may be relatively rigid and be carried by a rocker shaft 50 which extends along the partition wall 22 to the exterior of the hopper 20. The outer end thereof may be provided with a crank lever 52, whereby the closure member may be shifted or rocked within the confine of the lower portion of the chute 23.

As shown in Fig. 4, the valve mechanism is positioned whereby the closure member 45 is interrupting communication between the

3/8 inch storage bin 30 and the chute 23 and the closure member 46 is swung to the left whereby the exposed opening 47 establishes communication between the 3/8 inch chute 23 and the 1 inch storage bin 32. The 3/8 inch screenings thus pass directly from the screen cylinder 14 downwardly to the chute 23 and through the opening 47 and directly to the bin 32, and becomes commingled with the 1

10 inch screening dropping directly from the screening cylinder 15 to the storage bin 32. The portion 22^a of the partition wall 22 which is hingedly mounted is swung (in this case) to the right against the wall 21 thus permitting the screened sand falling from the cylinder 14 to fall one-half of the hopper.

If it is desired to have the various screened sizes separated, the rocker lever 20 may be swung to the right and thus bring the closure member 46 over the opening 47 and shift the closure member 45 backwardly to a position adjacent the bottom of the chute member 25, thus permitting the 3/8 inch screenings to flow directly into its storage bin 30. Positioning of the wall 22^a as shown in Fig. 2 reconditions the hopper for the reception and storage of four grades of screened material.

30 The particular valve arrangement illustrated, it will be observed, may be readily operated by the lever 52, the relation of the opening 47 to the bottom of the chute being such that any particles of material accumulated in the bottom of the chute, when the opening 45 is closed, may be readily brushed through the opening 47 to permit the closing thereof by swinging the member 46 thereover.

40 From the foregoing description of my invention, it will be observed that I provide a very simple device within a hopper construction whereby the hopper may receive a plurality of sizes of screened ma-

45 terial which may be directed to and stored in a plurality of bins formed by partition walls within the hopper. If it is desired to screen sand, substantially one-half of the hopper space may be utilized for the

50 storage of the screened sand by the operation of a simple valve mechanism and the swinging or removing of a partition wall within the hopper whereby screened sand may fall directly into a space correspond-

55 ing to two of the bin spaces of the hopper. The simplicity of the arrangement is such that the hopper may be readily conditioned for either the reception of graded sizes of material or for the reception of sand in a short period of time. It is to be understood that the idea of a valve arrangement and the removal of partition walls for establishing communication between the chutes and the various bins of the hopper

65 and means associated with the chutes and

the walls of the hopper for opening and closing passageways whereby the hopper may be readily conditioned for the storage of a plurality of sizes of graded materials or for the storage of sand, may be embodied 70 in constructions other than herein disclosed and which would come within the scope of the present invention.

I claim:

1. In a device of the character described, 75 a plurality of storage bins comprising a composite hopper adapted for reception of the various graded materials flowing from a screen and having discharge openings from which the material may flow by gravity, a chute for guiding material into a region adjacent two bins, and means for determining which of said two bins shall receive the material coming down the chute.

2. In a machine of the character described, 80 a sectional hopper adapted to be disposed beneath a screen, and having bins produced by the outside hopper wall and partition walls, whereby some of the screenings may be discharged directly into some 85 of the bins of said hopper, said hopper having fixed chutes located in certain bins for simultaneously guiding other grades of the screenings into other bins of the hopper, and means associated with said chutes 90 whereby a graded material flowing from the screen to its respective bin, may be diverted to the bin of another graded material.

3. In a machine of the character described, 100 a hopper having a plurality of bins adaptable for the reception of various grades of material, fixed chutes in the hopper for guiding the various grades of material to a region adjacent two bins, and means associated with the chutes for diverting the flow of one grade of material 105 from its bin into the bin of another grade of material.

4. A machine of the character described, 110 a hopper having a plurality of walls therein for dividing the hopper into a plurality of storage bins, openings formed in said walls establishing communication between the various bins and means associated with the walls for alternately exposing one opening 115 and closing the other, whereby material designated for one bin may be directed into a bin containing a material of a different grade.

5. In a machine of the character described, 120 a hopper adapted to be disposed beneath a screen, said hopper being divided into a plurality of storage bins adaptable for the reception of various graded materials flowing from the screen and having removable partition walls, whereby screened material of a common grade may flow from the screen into a space corresponding to two bin spaces.

6. In a sectional hopper of the character 125

- described means for guiding the grades of material to receiving bins of the hopper, means for selectively guiding a grade of material destined for one of the bins into the bin of another grade of material, and removable partitioning means defining the bins of the hopper whereby the storage capacity of the hopper for a particular screened material may be increased.
- 10 7. In a hopper of the character described, a plurality of dividing walls defining the storage bins of the hopper, means for guiding separate grades of material to the receiving bins of the hopper, means for diverting the flow of one grade of material into the bin of another grade of material, the partition wall defining the first-named bin, being removable, whereby the material destined for an adjacent bin may occupy 20 the space of two bins.
8. In a machine of the character described, a hopper being divided into a plurality of storage bins adaptable for the reception of various graded materials, and 25 having a hinged partition wall whereby the size of a bin space may be increased by swinging said wall into juxtaposition with another hopper wall.
9. In a machine of the character described, a hopper, walls within the hopper defining a plurality of storage bins therein, a material chute associated with one of such walls and extending downwardly and terminating at openings formed in adjoining 30 dividing walls of the hopper, and means for controlling said openings.
10. In a hopper of the character described, the combination with the surrounding outside hopper wall of a plurality of dividing walls radiating from a common axis and defining the storage bins of the hopper, a chute mounted on one of such dividing walls for guiding material through another 35 of such walls into the bin beyond the latter wall, and means at the lower end of the chute for diverting the flow of material from the last-mentioned bin into the bin of another grade of material.
11. A sectional hopper of the character described comprising an outer wall and partition walls radiating from a common axis to produce a plurality of bins grouped together to have vertical corners adjacent each other, each bin having an individual gravity discharge and means associated with one 50 bin adjacent the common corner for diverting material normally destined for that bin to another bin.
12. In a sectional hopper of the character described, the combination of a plurality of bins grouped together to have corners adjacent each other, an inclined chute in one of the bins leading downwardly alongside of one of the partition walls and a valve adapted to direct the discharge from the 55 chute laterally through the wall ahead of the chute or through a wall at an angle to such wall.
13. A sectional hopper of the character described comprising four rectangular bins 60 grouped together to have four corners adjacent each other, a chute in one of the bins leading to a region adjacent the common corner and means associated with said chute for diverting material normally destined for 65 one bin into another bin.
14. In a sectional hopper of the character described, the combination of four rectangular bins grouped together, to have corners adjacent each other, each bin having an inclined bottom wall leading to a gravity discharge, an inclined chute in one of the bins mounted on one of the partition walls, a valve adapted to direct the discharge from the chute laterally through the wall carrying the chute or through a partition at an angle to such wall, one of the partition walls other than that which carries the chute being movable.
- In testimony whereof, I hereunto affix my 80 signature.
- JAMES FARASEY.
